UNITED STATES PATENT OFFICE

2,227,041

MERCURY SWITCH BREAKER

Joseph H. Staley, Columbus, Ind.

Application August 8, 1938, Serial No. 223,625

4 Claims. (Cl. 200—152)

This invention relates to the art of mercury switches and particularly to that type employing a refractory member through or over which a column of mercury is severed to break the circuit, the refractory member being employed to control the location and quenching of the ensuing arc. The primary object of the present invention is to provide a refractory member for the purpose indicated which will have a form lending itself to insertion within a tubular member in conjunction with an iron or metal wall chamber at one end and an electrode at the other end, the structure being so arranged that a pool of mercury may be maintained in contact with the electrode without "after spill" so that once the circuit is broken, it will not be made by subsequent flow of mercury from that pool which might otherwise result upon further tilting or rocking of the switch.

The objects and advantages of the invention will be better understood by those versed in the art from the following description of the invention as illustrated in the accompanying drawing, in which

Fig. 1 is a central longitudinal section through a structure embodying the invention, in the closed circuit position;

Fig. 2, a similar view in open circuit position, and

Fig. 3, a view in perspective of the refractory member.

Like characters of reference indicate like parts throughout the several views in the drawing.

Reference is made to my co-pending U. S. patent application Serial Number 708,844, filed January 29, 1934, of which the present application is a continuation in part.

Referring to the drawing, in the particular embodiment of the invention herein illustrated, a metallic tubular body 10 is employed with a closed end 11 and a cap 12 is telescoped over the end of the body 10 to have an intervening, insulating sleeve 13. The cap 12 forms one electrode and the body 10 the other.

A refractory member 14, hereinafter called a breaker for convenience, is formed to have a generally cylindrical shape so as to be frictionally engaged within the end of the sleeve 13 to be between the cap 12 and the body 10 in respect to flow of mercury therebetween. This breaker 14 is made out of any suitable material which will withstand the tremendous heat of the electric arc without any appreciable deterioration and particularly as will not deteriorate to such

an extent as will cause any breaking down thereof to have particles or materials therefrom mixing with the mercury.

The particular arrangement of the breaker is important. It has a major internal bore 15 opening into the chamber of the body 10. It also has a minor bore 16 co-axial with the bore 15. This smaller bore 16 is at that end of the breaker 14 which is nearest to the end wall of the cap 12. There is the further important feature in connection with this breaker 14 of the extending boss 17 that has an external diameter less than that of the major portion of the breaker, and through which boss 17 the bore 16 is carried.

This structure provides an abrupt annular shoulder 18 at the junction of the minor bore 16 with the major bore 15, this shoulder being well back within the breaker at the internal end of the bore 15. The other important feature of

this structure is that by reason of the extending boss 17, the open end of the bore 16 may be carried in close proximity to the end wall of the cap 12 and at the same time there will be left between the breaker and the cap 12 a chamber

19 around the boss 17, in which chamber a sufficient quantity of mercury 20 may be retained regardless of the angle of tilting of the entire switch which will carry the current between that mercury and the cap 12 without heating beyond a predetermined amount. Also, as indicated in

comparing Figs. 1 and 2, when the switch is tilted from the closed position in Fig. 1 to the open position in Fig. 2, there will be no subsequent flow from this body of mercury 20 to the major body 21 since further tilting will only cause the mass of mercury 20 to extend further around the periphery of the boss 17.

The present application is directed toward this breaker 14 in its general association with a two-part metallic switch irrespective of the sealing

40 electrode employed in conjunction with the tubular body 10, this sealing electrode in the present instance being in the form of the telescoping cap although the invention is not intended to be

45 limited to that particular form.

As indicated in my co-pending application, Serial Number 708,844, above referred to, the bore 16 is so proportioned as to length, diameter, and spacing from the electrode 12 as to properly define the location of the break between the minor 50 and major masses of mercury 20 and 21 whereby the ensuing arc will occur within this smaller bore 16 and thereby be subject to the quenching effects produced.

While I have herein shown and described my

55

invention in the one particular form, it is obvious that there may be structural variations without departing from the spirit of the invention and I, therefore, do not desire to be limited to that precise form beyond the limitations as may be imposed by the following claims.

I claim:

1. In a mercury switch having a quantity of mercury and a pair of electrodes, one of which forms a tubular metallic chamber, a breaker positioned between the electrodes and in which the mercury flows to complete and break a circuit between the electrodes, said breaker having a cylindrical bore of substantially the same size of and leading from the said electrode chamber, an extension on the breaker of external diameter less than that of the breaker and having a second cylindrical bore of less diameter co-axially leading from the larger bore through said extension and opening concentrically of and toward the other electrode.

2. In a mercury switch having a quantity of mercury and a pair of electrodes, one of which forms a tubular metallic chamber, a breaker positioned between the electrodes and in which the mercury flows to complete and break a circuit between the electrodes, said breaker having a cylindrical bore of substantially the same size of and leading from the said electrode chamber, and having a second cylindrical bore of less diameter co-axially leading from the larger bore and opening concentrically of and toward the other electrode, said breaker further having a boss extending from that end having the smaller bore, which

bore continues through the boss, the boss having an external diameter less than that part of the breaker having the major bore, said boss being proportioned in relation to the other electrode to extend therein in spaced relation.

5

3. For a mercury switch, an insulating and arc-resisting member having a major cylindrical bore open from one end and terminating at its other end at a transverse wall, said member further having a minor cylindrical bore concentric of the major bore axis through said wall and opening at its end removed from the wall, said transverse wall being planer and normal to said axis defining a sharp shoulder about the minor bore orifice through the wall, and a boss having an external diameter reduced from that of the breaker and through which said boss said minor bore extends.

4. For a mercury switch, an insulating and arc-resisting member having a major cylindrical bore open from one end and terminating at its other end at a transverse wall, said member further having a minor cylindrical bore concentric of the major bore axis through said wall and opening at its end removed from the wall, said transverse wall being planar and normal to said axis defining a sharp shoulder about the minor bore orifice through the wall, and a cylindrical boss extending concentrically from said member from the minor bore end to have the minor bore pass centrally therethrough, the external diameter of the boss being less than that of the member.

JOSEPH H. STALEY.
